US00D896156S

(12) **United States Design Patent** (10) **Patent No.:** **US D896,156 S**
(45) **Date of Patent:** **** Sep. 15, 2020**

(54) **COUPLER FOR WINDSHIELD WIPER**

(71) Applicant: **TRICO PRODUCTS CORPORATION**, Rochester Hills, MI (US)

(72) Inventors: **Lindsey Tufts, Jr.**, Kent, OH (US); **David Boll**, Avon, OH (US); **Nicholas E. Stanca**, Westlake, OH (US); **Robert Soreo**, Cleveland Heights, OH (US); **R. Kenneth Thorstenson, IV**, Shelby Township, MI (US); **Dan Ehde**, Ortonville, MI (US)

(73) Assignee: **TRICO PRODUCTS CORPORATION**, Rochester Hills, MI (US)

(**) Term: **15 Years**

(21) Appl. No.: **29/687,795**

(22) Filed: **Apr. 16, 2019**

(51) LOC (12) Cl. **12-16**

(52) U.S. Cl.

USPC **D12/220**; D12/219

(58) **Field of Classification Search**

USPC D12/219-220, 400; 15/250.001, 246, 15/247, 250.4, 250.361, 250.19, 250.48, 15/250.03, 250.04, 250.31-250.33, 15/250.351, 250.38, 250.201, 250.451, 15/250.458, 250.07, 250.44

CPC B60S 1/4003; B60S 1/3801

(57) **CLAIM**

The ornamental design for a coupler for windshield wiper, as shown and described.

DESCRIPTION

FIG. 1 is an upper perspective view of a coupler for windshield wiper;

FIG. 2 is another upper perspective view thereof;

FIG. 3 is a right side view thereof;

FIG. 4 is a left side view thereof;

FIG. 5 is an end view thereof;

FIG. 6 is an opposite end view thereof;

FIG. 7 is a top plan view thereof; and,

FIG. 8 is a bottom plan view thereof.

The broken lines in the drawings depict portions that form no part of the claimed design.

1 Claim, 7 Drawing Sheets
